UNITED STATES PATENT OFFICE.

CYRUS D. FOYE, OF BEVERLY, MASSACHUSETTS, ASSIGNOR TO UNITED SHOE MACHINERY COMPANY, OF PATERSON, NEW JERSEY, A CORPORATION OF NEW JERSEY.

PINCERS.

1,051,322.

Specification of Letters Patent. Patented Jan. 21, 1913.

Application filed December 24, 1910. Serial No. 599,059.

To all whom it may concern:

Be it known that I, CYRUS D. FOYE, a citizen of the United States, residing at Beverly, in the county of Essex and State of Massachusetts, have invented certain Improvements in Pincers, of which the following description, in connection with the accompanying drawings, is a specification, like reference characters on the drawings indicating 10 like parts in the several figures.

This invention relates to pincer mechanisms herein shown as adapted for use in lasting machines of the type described in U. S. Letters Patent No. 1,005,234 granted 15 to Ladd and Stiggins and dated Oct. 10, 1911.

An object of this invention is to improve the construction of this type of pincers and particularly for the purpose of reducing the 20 cost of manufacture and rendering more accessible a part which requires renewal from time to time.

In the illustrated embodiment of the invention the pincers comprise a rigid jaw and 25 a pivoted jaw. The pivoted jaw is fulcrumed on a laterally extended link which connects it with the fixed jaw. The pivoted jaw is extended above its fulcrum and the upper arm is connected with an endwise 30 movable operating rod by means of a link to actuate the pivoted jaw in the curved path necessary for its movement with the fulcrumed link. A cam is provided back of the pivoted jaw, or between it and the carrier 35 for the fixed jaw, and the upper end of the pivoted jaw has a formation for engagement with this cam to effect rocking movement of the pivoted jaw about its connection with the fulcrumed link during the closing 40 movement of the pivoted jaw. For the purpose of maintaining this engagement with the cam and for controlling flexure of the link connection with the operating rod a spring is arranged in accordance with this 45 invention for engagement with the operating rod and the connecting link. This spring is shown as located on the outer side of these members as they are arranged in the assembled pincer so that it is readily accessible 50 for renewal. As shown, the spring has a staple-like formation and is supported by one of said members and presses against the other member in a direction to tend to cause flexure toward the cam and, by force transferred through the link, to maintain the heel

of the pivoted gripper jaw against its controlling cam. A preferred mounting for the spring comprises an eye in the operating rod which receives one leg of the staple and an angular recess adjacent to said eye into 60 which the other leg of the staple may be introduced laterally and will be held by the resilience of the staple while a head on said other leg engages with a wall of the angular recess to uphold the spring. The cross bar 65 or head of the staple-shaped spring bears laterally against the outer face of the connecting link.

The invention will more clearly appear from the following description of the mechanism embodying the same and it will then be pointed out in the claims.

Figure 1 is a perspective view of a portion of a pincer mechanism embodying this invention. Fig. 2 is a side elevation of the 75 lower portion of the pincers with a part of the casing broken away. Fig. 3 is a view similar to Fig. 1 showing a modification.

The pincer jaw 16, which is pivoted about midway of its whole length upon the 80 swinging bar 70, is connected at its upper end by a link 72 to its operating rod 15 in order that the tip of the jaw may have an appropriate outreaching movement to gather in the stock which is to be gripped. 85 The heel 71 of jaw 16 slides over a cam 74 which is formed to coöperate with these connections for giving the desired path of movement and in accordance with a feature of this invention a spring is arranged to 90 coöperate with the link 72 and the foot of the rod 15 for controlling flexure of the joint between said link and rod for the purpose of maintaining the heel 71 against the cam 74. This spring which is indicated 95 at 75 in Figs. 1 and 2 has an inverted staple shape and its cross bar is seated against the outer face of the link 72 with its legs extending upwardly through bosses on the foot of the rod 72 and one of the legs has 100 its upper end outturned as at 76. For convenience in assembling the uppers and permitting removal and replacement of the spring without disconnecting the grippers a close fitting eye is made in the boss on the rod foot to receive the straight leg of the spring which is thrust upwardly there-through. For receiving the other leg the boss is slotted inwardly and then laterally 105 to form a seat into which the leg having the 110

outturned end 76 can be inserted laterally and will be held by the resilience of the spring with the outturned end 76 resting down upon the upper face of the boss. The 5 legs of the staple are bent inwardly at 77 to form shoulders which limit the upward movement of the legs in the boss and thereby prevent the spring from working upwardly while in use. In the construction 10 illustrated in Fig. 3, the legs of the staple extend through straight eyes in a boss that is formed on the outer face of the link 72 and the ends of the legs rest against the foot of the rod 15 while the cross bar of the 15 staple is seated in a retaining recess in a link which prevents the spring from accidentally moving downwardly.

For removing the spring from the construction shown in Fig. 3 it is only necessary to pry the cross bar out of its seat and 20 drive the staple downwardly by force applied to its ends. For removing the spring from the construction shown in Figs. 1 and 2 it is only necessary to pinch the legs together until the leg having the outturned end can be moved laterally out of its recess whereupon the spring can be freed from the grippers by a downward movement. Reverse manipulation effects quickly the replacement of this spring.

Having explained the nature of the invention and described how it may be embodied in practical form, I claim as new and desire to secure by Letters Patent of 35 the United States:

1. In a lasting machine the combination with suitable actuating mechanism, of a pincer jaw, a coöperating pivoted jaw, means for actuating the pivoted jaw to

grip the stock, said means comprising a 40 rod, a link pivotally connecting the rod and the jaw, a cam for engagement by the upper end of the jaw, and a spring engaging the rod and the link and supported by one of said members to maintain the jaw against 45 the cam.

2. In a lasting machine the combination with suitable actuating mechanism, of a pincer jaw, a coöperating pivoted jaw, means for actuating the pivoted jaw to 50 grip the stock, said means comprising a rod, a link pivotally connecting the rod and the jaw, and a staple shaped spring having its bar in engagement with the link and having one leg outturned at its end, an eye in 55 the rod to receive the other leg and an angular recess in which the leg having the outturned end is held by the resilience of the spring.

3. In a lasting machine the combination 60 with suitable actuating mechanism, of a pincer jaw; a coöperating pivoted jaw, means jointed to the pivoted jaw for actuating that jaw to grip the stock and a spring supported on one of said parts and 65 engaging the other to control the flexure between said pivoted jaw and its actuating means, the spring being carried on the outer side of its supporting part in a position easily accessible for replacement and 70 engaging the outer side of the other part.

In testimony whereof I have signed my name to this specification in the presence of two subscribing witnesses.

CYRUS D. FOYE.
